UNITED STATES PATENT OFFICE.

CHARLES A. MILLER, OF COVINGTON, KENTUCKY, ASSIGNOR TO THE WELDERS SUPPLY & MFG. CO., OF CINCINNATI, OHIO, A CORPORATION OF OHIO.

TORCH TIP.

Application filed March 21, 1925. Serial No. 17,299.

To all whom it may concern:

Be it known that I, CHARLES A. MILLER, a citizen of the United States, residing at Covington, Kenton County, and State of Kentucky, have invented certain new and useful Improvements in Torch Tips, of which the following is a specification, reference being had to the accompanying drawings.

This invention relates to certain improvements in torch tips and has relation more particularly to a tip of this general character especially designed and adapted for use in connection with cutting torches and it is an object of the invention to provide a novel and improved device of this general character which will not flash back and wherein the gases will not explode.

Another object of the invention is to provide a novel and improved device of this general character which is made from one solid piece of material and wherein separate chambers are provided for the gases.

The invention consists in the details of construction and in the combination and arrangement of the several parts of my improved torch tip whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a longitudinally sectional view taken through a tip constructed in accordance with an embodiment of my invention;

Figure 2 is a view in end elevation of the device as herein disclosed;

Figure 3 is a sectional view taken substantially on the line 3-3 of Figure 1, looking in the direction of the arrow.

As disclosed in the accompanying drawings, T denotes my improved tip in its entirety, formed of one piece of material and preferably copper and which is provided at one end portion with the peripheral threads 1 to permit the proper application of the tip to the head. The device is also provided at a point inwardly of but in close proximity to the threads 1 with an enlargement 2 provided with flat faces whereby a suitable im-

plement may be engaged therewith to facilitate the applying or removing of the tip with respect to the head. The tip T is provided with a central bore 3 through which the cutting oxygen is adapted to flow, the inner or inserted end portion of the bore 3 being enlarged as at 4 providing a chamber to facilitate the flow of such oxygen through the bore 3.

At spaced points along the threaded portion 1 of the tip, the periphery is provided with the annular recesses 5 and 6 each of which being in communication through the medium of the ports 7 with the jet openings 8 drilled within the outer end of the tip and preferably equi-distantly spaced around the bore 3. The recess 5 provides a chamber which initially receives the acetylene gas and where such gas enters the tip and flows without any hindrance or obstruction to the outer point or working end of the tip. The second recess 6 provides a chamber to receive oxygen and through which such gas flows to the outer or tip end of the burner. By this arrangement the heating gas and the oxygen gas are effectively mixed before reaching the point or working end of the tip whereby flash back is prevented and also whereby the possibility of explosion is avoided. This is of particular advantage for the reason that after an explosion or flash back occurs, the tip is burned making it necessary to shut off the gas, allowing the work to become cold and therefore making it necessary to start all over and preheat again.

It is to be particularly noted that the threaded part 1 of the tip at all points is of the same diameter so that when such threaded part or portion is threaded within the head of the burner, the recesses or chambers 5 and 6 will be closed or sealed and it is to be further noted that the distance between the inner face of the enlargement 2 and the outer end of the threaded portion 1 is such that said inner face of the enlargement 2 will contact with or seat against the end of the head at the same time the outer end of the threaded portion 1 of the tip contacts with or seats against the inner end of the socket of the head in which the threaded portion of the tip is engaged. This structure is of particular advantage as only the two seats are required and together with the threaded portion 1, a tip is provided which

is highly efficient for the purpose designed yet is capable of being produced at a minimum of expense and effectively applied with a minimum of labor.

5 From the foregoing description it is thought to be obvious that a torch tip constructed in accordance with my invention is particularly well adapted for use by reason of the convenience and facility with 10 which it may be assembled and operated, and it will also be obvious that my invention is susceptible of some change and modification without departing from the principles and spirit thereof and for this reason I do not 15 wish to be understood as limiting myself to the precise arrangement and formation of the several parts herein shown in carrying out my invention in practice except as hereinafter claimed.

20 I claim:—

1. As a new article of manufacture, a tip 25 for a cutting torch formed of one piece of material and having a central bore there- through for the passage of a cutting gas, one end portion of the tip being insertible 30 within the torch, said end portion being threaded and provided at longitudinally spaced points along said threaded portion with annular recesses to provide chambers, 35 when the tip is in applied position, and jet openings leading from the outer or working end of the tip, each of said chambers having ports in communication with said openings for the passage of either an oxidizing gas or a heating gas, said threaded portion at all 40 points therealong aside from the recesses being substantially the same diameter.

2. As a new article of manufacture, a tip 45 for a cutting torch formed of one piece of material and having a central bore there- through for the passage of a cutting gas, one

end portion of the tip being insertible within the torch, said end portion being threaded and provided at longitudinally spaced points along said threaded portion with annular re- 45 cesses to provide chambers when the tip is in applied position, and jet openings leading from the outer or working end of the tip, each of said chambers having ports in com- 50 munication with said openings for the pas- sage of either an oxidizing gas or a heating gas, said threaded portion at all points there- along aside from the recesses being of sub- 55 stantially the same diameter, the end of the bore remote from the working end being enlarged to form a chamber when the tip is applied.

3. As a new article of manufacture, a tip 60 for a cutting torch formed of one piece of material and having a central bore there- through for the passage of a cutting gas, one end portion of the tip being insertible within the torch, said end portion being threaded and provided at longitudinally spaced points along said threaded portion with annular recesses to provide chambers, 65 and jet openings leading from the outer or working end of the tip, each of said cham- bers having ports in communication with said openings for the passage of either an oxidizing gas or a heating gas, said tip out- 70 wardly of the threaded portion but in rela- tively close proximity thereto being pro- 75 vided with an enlargement, said enlargement being adapted to contact with a face of the head in which the threaded portion is en- gaged and also providing means to apply or remove the tip.

In testimony whereof I hereunto affix my signature.

CHARLES A. MILLER
